UNITED STATES PATENT OFFICE.

FRANK W. WHITCHER, OF BOSTON, MASSACHUSETTS, ASSIGNOR TO HIMSELF, SANFORD CRANDON, OF MELROSE, AND HERBERT L. TURNER, OF MALDEN, MASSACHUSETTS.

DESIGN FOR A RUBBER SOLE.

SPECIFICATION forming part of Design No. 29,857, dated December 20, 1898.

Application filed November 16, 1898. Serial No. 696,651. Term of patent 14 years.

To all whom it may concern:

Be it known that I, FRANK W. WHITCHER, a citizen of the United States, residing at Boston, in the county of Suffolk and State of Massachusetts, have invented and produced a new and original Design for Rubber Soles for Boots and Shoes, of which the following is a specification, reference being had therein to the accompanying drawings.

Figure 1 is a view of the under face of a rubber sole, showing my new design. Fig. 2 is a view in section on the line 2 2 of Fig. 1. Fig. 3 is a view in section on the line 3 3 of Fig. 1. Fig. 4 is a view in section on the line 4 4 of Fig. 1.

As shown in the drawings, the leading or material features of my design comprise the general contour, which is that of the tread portion and shank portion of a shoe-sole, the corresponding portions herein being design-

nated 1 and 2, respectively, the oval-shaped field 3, having a raised and uneven surface, the disk 4 in said field and its inclosing margin 5, the transverse curvature of the sole shown in the sectional view Fig. 2, the transverse curvature of the shank shown in Fig. 3, and the longitudinal curvature which is shown in Fig. 4.

Having described my invention, what I claim as new, and desire to secure by Letters Patent, is--

The design for a rubber sole for boots and shoes, as herein shown and described.

In testimony whereof I affix my signature in presence of two witnesses.

FRANK W. WHITCHER.
